UNITED STATES PATENT OFFICE.

WILLIAM MANDERFIELD, OF COMFREY, MINNESOTA.

EXPANDING POST.

1,370,334.

Specification of Letters Patent.

Patented Mar. 1, 1921.

Application filed July 1, 1920. Serial No. 393,288.

To all whom it may concern:

Be it known that I, WILLIAM MANDERFIELD, a citizen of the United States, residing at Comfrey, in the county of Brown and 5 State of Minnesota, have invented certain new and useful Improvements in Expanding Posts; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to anchoring means for posts, stakes or the like or for any other member inserted in the ground or into wood, such as railroad spikes.

20 An object of this invention is to provide an improved anchor which is positive in its anchoring and easily constructed is entirely removed from the surface of the member being anchored and is of simple and cheap 25 construction.

With these and other objects in view, the invention consists in the construction, the combination, the detail and arrangement of parts as hereinafter more fully described 30 and claimed.

In the drawings,

Figure 1 is a side elevation of a stake provided with my improved device.

Fig. 2 is a section medial through Fig. 1, 35 and

Fig. 3 is a view similar to Fig. 2, with the anchor extended into anchoring position.

In the embodiment of my invention, I 40 provide a longitudinal channel 2 in a stake or other member to be anchored, 3. The longitudinal channel 2 branches to form a Y, the branches being designated by the numerals 4 and 4', and I provide to be inserted in the said longitudinal channel a single 45 wire member 5, which is bent at 6 to form a pair of closely setting sides which are held at their ends yieldingly outward as at 7, so as to normally straddle the point 8 of the Y and which are passed through a perforation 9 of a slot headed member 10. I also provide a cylindrical member 11, fitting 50 said longitudinal recess 2 and provided with a tongue 12 to fit in the slot of the said slot headed member 10 and which is provided

with a head 13 for driving the said anchor 55 5 downward, whereupon the said anchor spreads upon the point 8 and one end falls in the channel 4 and the other end in the channel 4' into the position shown in Fig. 3. In inserting the said anchor 5 into said 60 longitudinal slot, it is dropped therein and afterward the cylindrical member 11 is inserted until the tongue 12 engages in its slot, whereupon both members are turned by the turning of the head 13 until the points of 65 the member 5 drop into the channels 4 and 4'. Then by the striking of a hammer upon the head 13, the branches of the member 5 are distorted and driven outward to form an anchor.

70

What I claim is:

1. A post having a substantially axial opening, circular in cross section, diverging into openings in the opposite sides of the post, adjacent the lower end, an expanding 75 member bent upon itself, presenting juxtaposed substantially parallel arms, and a driving head connected at the bend and presenting a tool-receiving orifice, having a position-determining relation to the juxtaposed extremities.

2. A post having a substantially axial opening, circular in cross section, extending throughout the major portion of its length and diverging adjacent the lower end by the 85 formation of a wedge shaped intermediate portion, said openings terminating in the opposite sides of the post, an expanding member bent upon itself, presenting juxtaposed substantially parallel arms, and a 90 driving head connected at the bend and presenting a tool-receiving orifice having a position-determining relation to the juxtaposed extremities.

3. A post having a substantially axial 95 opening, circular in cross section, diverging into openings in the opposite sides of the post adjacent the lower ends, an expanding member bent upon itself, presenting juxtaposed substantially parallel arms, and a 100 driving head proportioned to substantially fill the opening, connected at the bend and presenting at its extremity a tool-receiving orifice having a position-determining relation to the juxtaposed extremities.

In testimony whereof I hereunto affix my signature.

WILLIAM MANDERFIELD.
